UNITED STATES PATENT OFFICE.

JOHN H. CREMER, OF BRADDOCK, PENNSYLVANIA.

APPARATUS FOR DRYING AIR.

SPECIFICATION forming part of Letters Patent No. 339,619, dated April 13, 1886.

Application filed September 12, 1885. Serial No. 176,885. (No model.)

To all whom it may concern:

Be it known that I, JOHN H. CREMER, a subject of the King of Holland, residing at Braddock, in the county of Allegheny, State 5 of Pennsylvania, have invented certain new and useful Improvements in Apparatus for Drying Air for Metallurgic Operations; and I do hereby declare the following to be a full, clear, and exact description of the invention, 10 sufficient to enable others skilled in the art to make and use the same.

Atmospheric air contains more or less watery vapor in suspension, the quantity thereof varying from about 0.25 to over 1.00 per cent. 15 The presence of watery vapor is oftentimes a serious detriment in many industrial operations involving the use of atmospheric air, and noticeably is this true in the working of smelting or blast furnaces for the reduction of iron from its ores. The water, coming in contact with the highly-heated coal, coke, iron, or other metal, is immediately decomposed, absorbing from the fuel a large quantity of heat and also oxidizing the metals. 25 Such disturbing reactions give rise to annoying perturbations in the working of the blast-furnace, developing a high heat in the stack, making the charge to "scaffold," and otherwise affecting the even reduction of the metal. 30 When the product of the furnace is run directly therefrom and is used in molten condition to charge the Bessemer converter, it is necessary that within definite limits the percentage composition of the furnace product 35 be carefully maintained; but such uniformity in condition, always difficult to accomplish, is rendered much more so by reason of the variable and uncertain quantity of watery vapor coming into the furnace with the air-blast and 40 developing therein the disturbing influences heretofore detailed. Hence it is the object of my invention to eliminate this source of error by depriving the air-blast practically of its contained moisture; and, while I shall describe 45 my invention hereinafter with particular reference to its use in connection with the blast-furnaces, it will be understood that the benefits thereof are not restricted to such special application, but that said invention may also 50 be adapted to other purposes—as, for instance, in conjunction with cupola-furnaces, Bessemer

converters, &c.—where it is desired to deprive the air-blast of its moisture.

My invention consists in providing the blast or like furnace with one or more desiccating 55 or drying chambers, through which the air-supply passes and wherein it is deprived of its contained moisture prior to the entry of the air into the furnace, said desiccating-chambers being arranged on the regenerative 60 plan, so that while one or more may be in use the others of the system are being restored to working condition.

The nature of my invention and the preferred construction to embody the same will 65 more fully appear from the following description, and will be thereafter definitely stated in the claims at the conclusion thereof.

In the accompanying drawings, forming part of this specification, Figure 1 is a longitudinal section, and Fig. 2 a transverse section, of one of the desiccating-chambers. Figs. 3 and 4 are like views, respectively, of a modified form of the same. Fig. 5 is a plan view of a series of the desiccating-chambers 75 and adjuncts Figs. 1 and 2, in connection with the air-trunk or main leading to the furnace; Fig. 6, an end elevation of one of the chambers and of the air-main.

The desiccating-chamber A, conveniently 80 of rectangular form, may consist, preferably, of sheet-metal plates stoutly secured together to constitute a closed compartment, said compartment serving to obtain the materials for abstracting the moisture from the air-current. 85 This material may be concentrated sulphuric acid, calcic chloride, or such like substances possessing the desired property of absorbing moisture, although in practice the calcic chloride is deemed best suited for the purpose. 90

The exposed surfaces of the chamber, and the pans, trays, or grids for holding the drying material may be coated or lined, if necessary, to prevent corrosive action.

In using the chloride or calcium it is proposed to arrange a series of trays, one above the other and extending across the chamber A, as shown, with suitable space between the trays to allow conveniently for charging the materials thereon, and also for the free sweep 100 of the air-currents over the same. The trays may be of any suitable size or capacity, de-

pendent upon the volume and velocity of the passing current, and can be sustained in position by any convenient or well-known means. The inlet-port b closed by door or valve, as at 5 b' , admits the air-supply to chamber A, while an outlet-pipe, b^2 , provided with suitable shut-off valve, b^3 , serves to conduct the air therefrom into the trunk or main c , Figs. 5 and 6, with which trunk the blower or pump 10 is connected. It is obvious that in some instances the inlet-port b , instead of opening directly from the air, as shown, may be connected by flue similar to pipe b^2 with the exit of the blower or force-pump. In such event 15 the air would be forced into instead of being drawn through the chamber A, while the trunk or main c , receiving the desiccated air, would deliver the same directly to the oven or regenerator, or, if no heating of the air is practiced, 20 then directly to the furnace. Whichever plan be adopted, the air passing through the chamber A in direct contact with the surface of the desiccating material has substantially all of its moisture abstracted, so that the deleterious 25 effects due to the presence of such moisture are no longer experienced. After more or less exposure the calcium chloride becomes saturated and sluggish in its action, so that it is necessary to renew or revivify the same. This 30 regeneration of the desiccating material may be accomplished efficiently and quickly *in situ* by either one of the following means: In Figs. 1 and 2 the trays a are shown to have a hollow shell or jacket, a^3 , extending beneath the 35 bottom, into which conveniently at opposite diagonal ends open the inlets a' and a^2 of the supply-pipes d and discharge-pipes d' , respectively. Hot air from the ovens, or hot furnace gases or steam may be delivered by main 40 pipe D to these several supply-pipes d , and thence to the jackets a^3 , imparting heat to the calcium chloride on trays a and driving off the absorbed moisture. The waste air, gases, or steam pass from the jackets a^3 by exits d' and 45 pipes D' to any convenient point. During the period of regeneration it will be understood that the valve b^3 in pipe b^2 is closed, so that the desiccating-chamber is practically out of service. To provide for such contingency 50 it is seen from Fig. 5 that there is a series of separate chambers, A, communicating with the trunk c , any one or more of which may be used, as desired, in desiccating the air-supply, while the others are shut off either for regeneration 55 or repairs. Thus chambers Nos. 1 and 3 may be worked, while Nos. 2 and 4 are being revivified, and vice versa.

The valve b' and the man-hole e in chamber A may be opened during regeneration to admit of a local air circulation sufficient to carry away the vapor which is thrown off from the saturated desiccating material.

In Figs. 3 and 4 the regeneration of the inert desiccating materials is shown to be effected not by the use of jackets beneath the trays a , as in Figs. 1 and 2, but by means of the direct contact of hot air or waste furnace-

gases blasted into chamber A from the main F, and passing therefrom by the man-hole e . Valve f and lid e' close the main F and the man-hole, respectively, during the time that the chamber is working in the desiccation of the air.

By either of the expedients heretofore set forth or like suitable means, it becomes possible to revivify the desiccating material *in situ*, and, as appears, to do this economically by utilization of the waste furnace-gases, spent steam, &c., either meditately or immediately, and in such manner as not to interfere with the regular and continuous working of the furnace. A single charge of desiccating material may obviously serve, by careful management, for a long period of use.

Other forms of drying-chamber may be adopted than are set out herein without departing from the spirit of my invention. Thus the calcium chloride might be molded into brick form with use of a little clay and coal-dust to give consistency, the dried bricks being arranged in an upright chamber exactly as in a Whitwell hot-air stove, a layer of common brick sustained from the side walls being arched at regular stages to sustain the rows of desiccating-brick next above. The regeneration of such type of drying-chamber would proceed exactly as now occurs in the Whitwell regenerative stove—that is, one compartment would be desiccating the air-supply and at the same time the other compartment, under the high heat of the waste furnace-gases circulating therein, would be parting with the excess moisture.

Instead of having each desiccating-chamber to connect with the air-trunk by its own individual outlet-pipe, as shown in the drawings, any two of such outlet-pipes may be joined together and lead thence by a single branch flue to the main. A butterfly or like valve, as commonly employed in the ordinary hot-air regenerator-chambers of the Siemens system, being located at the junction of the outlet-pipes and the branch flue, it is clear that either one of the set of desiccating-chambers may, as before, be established thereby in separate communication with the air-main, while at the same time the companion chamber can be cut off therefrom by proper position of the controlling-valve. Whatever construction be adopted, so long as the desiccating-chambers are used alternatively and regeneratively, the working of the furnace continues uninterrupted, and the benefits of my invention are to be derived.

Heretofore it has been proposed to employ a desiccating apparatus in conjunction with a smelting-furnace, through which apparatus the air-blast was designed to pass for the purpose of abstracting the moisture therefrom prior to the introduction of the air into the furnace; but in such earlier apparatus the desiccant, instead of being disposed in separate compartments or chambers, as in my invention, so as to be regenerated *in situ* with-

out arresting the continuous operation of the furnace, was retained in bulk within a single stack or chamber resembling an ordinary cupola in construction. In such devices no regeneration of the desiccant was attempted or was practicable. The desiccant wasted away to solution and the air admitted to the lower part of the stack became surcharged with moisture from the deliquescent material there accumulated, and speedily and wastefully impaired the fresh supply as it rose through the same in passing to the exit from the stack. Moreover, since the air must force its way through the entire body of desiccating material charged in irregular masses and at various intervals into the stack, the resistance to be overcome was much increased and differed greatly according to the height or state of the desiccants within the chamber. The even operation of the blowing-engine and of the furnace was accordingly disturbed, involving more risk and care in attendance thereon than should be necessary in the best practice.

I am not aware that prior to my invention any apparatus had been devised which would fulfill the conditions desired, or whereby the same desiccants could be frequently revivified and reused *in situ* without handling and without the expense of large additional fresh charges at the same time that the working of the furnace with dried air continued uninterrupted.

It should be understood that the process of drying air for metallurgic operations, as detailed herein, forms no part of the present application, but is made the subject of a separate application now on file in the United States Patent Office. The present case is restricted to the novel features of structure described, which constitute the preferred means for carrying such process into effect.

Without limiting myself to the precise details of structure hereinbefore set forth, and having thus described the invention, what I claim as new, and desire to secure by Letters Patent, is—

1. The combination, with the air trunk or main leading to the smelting-furnace or the like, of two or more desiccating-chambers communicating separately with said main,

and provided with suitable valve mechanism whereby the air-supply may alternately pass through one or more of said chambers to be desiccated, and be cut off from the other of said chambers to allow for regeneration thereof, substantially as described. 55

2. The combination, with the air-trunk or main leading to the furnace, of the desiccating-chamber connected therewith and having suitable valves to control its communication with the atmosphere and main, respectively, said chamber being provided with a series of shelves to contain the desiccating materials, and with supplemental inlet and outlet passages; whereby the excess moisture of the desiccants may be driven off, substantially as described. 60 65

3. The combination, with the desiccating-chamber having the series of hollow jackets, trays, or shelves arranged therein, of the supply and discharge pipes communicating with said jackets, substantially as described. 70

4. The combination, with the air trunk or main leading to the smelting-furnace or the like, of two or more desiccating-chambers 75 communicating separately with said main, said chambers being provided with a series of shelves to contain the desiccating material, and with suitable valve mechanism whereby the air-supply may alternately pass through 80 one or more of said chambers to be desiccated and be cut off from the other of said chambers to allow for regeneration, substantially as described.

5. The combination, with the air trunk or main leading to the smelting-furnace or the like, of two or more desiccating-chambers communicating separately with said main, said chambers being provided with means, substantially as described, for the regeneration thereof, and with suitable valve mechanism, whereby, during such regeneration, the air-supply will pass through the companion chamber or chambers for desiccation, substantially as set forth. 85 90
